LARS HANSON, OF DRISCOLL, NORTH DAKOTA.

WINDMILL AND PUMP ROD CONNECTION.

1,176,341.

Specification of Letters Patent. Patented Mar. 21, 1916.

Application filed May 8, 1915. Serial No. 26,885.

To all whom it may concern:

Be it known that I, HERBERT H. CHAPIN, a citizen of the United States, residing at Driscoll, in the county of Burleigh and State of North Dakota, have invented certain new and useful Improvements in Windmill and Pump Rod Connections, of which the following is a specification, reference being had to the accompanying drawings.

10 This invention comprehends certain new and useful improvements in windmill and pump rod connections, and has for its primary object a durable and efficient construction of device of this character whereby the application of a pump jack or pump handle to the device will automatically disconnect the pump rod from the windmill rod so that the pump may be freely operated by hand or by the jack, and whereby, when the pump 15 handle or jack is disconnected, the pump rod and windmill rod will be automatically coupled together. And the invention also aims to generally improve devices of this class so as to render them more useful and 20 commercially desirable.

25 With the above and other objects in view, as will more fully appear as the description proceeds, the invention consists in certain constructions, arrangements and combinations of the parts that I shall hereinafter 30 more fully describe and claim.

For a full understanding of the invention, reference is to be had to the following description and accompanying drawing, in 35 which—

Figure 1 is a side elevation of a pump rod connection and pump rod operating means made in accordance with my invention; Fig. 2 is a similar view to Fig. 1, but on a larger 40 scale and showing the parts in section; Fig. 3 is a front view of the connection between the trip device and the pump rod, the pump rod guide and the handle being in section: Fig. 4 is a fragmentary front elevation of 45 the lower end of the windmill rod and the coupling 9 attached thereto.

Corresponding and like parts are referred to in the following description and designated in all of the views of the accompanying drawing by like reference characters.

50 Referring to the drawing, the numeral 1 designates a pump rod to which is pivotally

connected a trip device 2, said trip device in the present embodiment of the invention, comprising two longitudinally disposed 55 bars 3 that are mounted on opposite sides of the pump rod 1 and that are pivotally connected thereto intermediate of their ends, as indicated at 4. The trip device 2 also comprises a back brace, or transverse bar 5 60 which connects the two longitudinal bars together near their lower ends and a transversely extending rod 6 connecting the longitudinal bars together at or near their upper ends, said rod being designed to enter 65 a slot 7 formed in the pump rod 1 near the upper end thereof and also in slots 8 that are formed in the lower end of a coupling 9 designed to be secured by bolts or the like to the lower end of the ordinary wooden 70 windmill rod 10.

Secured to the pump rod 1 is a spring 11, said spring being held at varying and required degrees of tension against one edge of the pump rod 1 by means of a tensioning 75 device 12. Preferably the free end of the spring 11 is curled or curved slightly away from the adjoining edge of the pump rod.

13 designates the pump handle. This is preferably forked at one end, as best illustrated in Fig. 3, and carries in the fork a transversely extending pin 14, adapted to be forced back of the spring 11 and down between the same and the adjoining edge of the pump rod 1 so as to be finally received 80 in a recess 15 formed in said edge, as indicated in the drawing. Coiled springs 16 are disposed on opposite sides of the pump rod and connected to the longitudinal bars 3 of the trip device 2, said springs exerting a 85 tension on the trip device so as to move the same in a direction to bring the lower ends of the bars 3 into registry with the recess 15 and the rod 6 into the recesses 7 and 8 when the same register, to operatively connect the 90 pump rod and windmill rod together.

From the foregoing description in connection with the accompanying drawing, the operation of my improved windmill rod and pump rod connection will be apparent. 100 In the practical use of the device, when it is desired to pump by hand, the handle 13 is manipulated to bring the pin 14 back of the spring 11 and into the recess 15, this op-

eration serving to cause the forked extremities of the handle 13 to ride upon the longitudinally disposed cams 17 formed on or secured to the lower ends of the bars 3, or 5 formed by the lower edges of said bars themselves, whereby the trip device will be automatically tilted to carry the rod 6 out of the slots 7 and 8 and thus disconnect the pump rod from the windmill rod to allow 10 of the free operation of the pump by hand. Whenever it is desired to again connect the pump rod to the windmill rod, it is only necessary to pull back slightly on the pump handle to move the pin 14 out of the recess 15 whereupon the springs 16 will be permitted to act and just as soon as the windmill rod in its subsequent upward movement brings its recess 8 into registry with the recess 7, the rods 6 will enter said registering 20 recesses and the windmill rod and the pump rod will thus be automatically coupled together.

In order to detachably connect the pump rod to a pump jack operated by an engine, 25 and to automatically disconnect the pump rod from the coupling 9 at the time that the connection between the pump jack and pump rod is made, I may form the pump rod 1 above the pivot bolt 4 with the recess 30 18 which is normally closed by the upwardly extending flat spring 19 which is outwardly curved at its upper end in the same manner as the spring 11 heretofore referred to. The pump jack is designated generally 20, only 35 a portion of the pump jack being shown. This pump jack is preferably bifurcated and formed with the transversely extending bolt or rod 21, which, when the end of the pump jack is depressed, engages behind the spring 40 19 and in the recess 18. Upon the downward movement of the pump jack 20 so as to carry the bolt 21 into engagement with the recess 18, the rounded end of the pump jack will force the upper end of the trip device 2 45 outward, thus disconnecting the bolt 6 from its connection with the coupling 9 and thus disconnecting the pump rod from the windmill.

I preferably mount upon the rod 1 below 50 the pivot bolt 4 the spring 22. This spring is a square coil spring and is fastened to the pump rod at its upper end. The object of this spring is to hold the pump rod up about one-half an inch at the lowest point. 55 The lower end of this spring upon a downward movement of the pump rod engages the top of the pump rod guide 23. Therefore, in making connection with the pump jack and pump rod, the pump rod has a 60 chance to give or spring, and this lessens the wear and jolt of the pump rod.

While the accompanying drawing illustrates what I believe to be the preferred em-

bodiment of the invention, it is to be understood that the invention is not limited thereto, but that various changes may be made in the construction, arrangement and proportions of the parts without departing from the scope of the invention as defined in the appended claims.

What is claimed is:

1. The combination with a windmill rod and pump rod, each having a slot, of a trip device comprising bars arranged upon opposite sides of the pump rod and pivotally connected intermediate of their ends, and a cross rod adapted to enter the slot of the windmill rod, the lower ends of the bars being adapted to extend over the pump rod slot, a lever provided with a pin receivable in said pump rod slot for engagement with said bars, whereby the trip device will be moved in a direction to carry the cross rod out of the windmill rod slot, and means tending to move said trip device in the opposite direction.

2. The combination with a windmill rod and a pump rod, of a trip device embodying bars pivotally connected intermediate of their ends on the sides of the pump rod, and a cross rod connected to said bars near the upper end of the latter and engageable with the pump rod to connect the trip device thereto, a spring carried by the pump rod, a lever designed to engage with said spring and arranged, upon such engagement, to also engage the bars at the lower end of the latter, whereby the trip device will be forced in a direction to disconnect the cross rod from the windmill rod.

3. The combination with a windmill rod and pump rod, of a trip device comprising bars pivotally connected intermediate of their ends to opposite sides of the pump rod, and a cross rod connected to said bars at their upper ends and engageable with the windmill rod, the pump rod being formed with a recess, a spring secured to the pump rod and extending across said recess, a lever provided with a cross pin adapted to extend back of said spring when the handle is moved down into the recess, whereby the end of the handle will engage said pivoted bars and tilt the trip device, said pivoted arms being provided at their lower ends with cams upon which the end of the handle rides and spring means tending to move the trip device in the opposite direction.

4. The combination with a windmill rod and pump rod, each having a slot, of a trip device comprising bars arranged upon opposite sides of the pump rod and connected intermediate their ends, a cross rod carried by the bars adapted to enter the slot of the windmill rod, said pump rod having a slot

therein upon the opposite side of the rod from the first notch, a spring normally engaged over the last named slot, and a pump jack including spaced bars, a rod connecting said bars and adapted to be engaged behind said spring and disposed within said last slot, the ends of the pump jack bars engaging the bars of the trip device,

whereby to disconnect the rod from the windmill rod.

In testimony whereof I hereunto affix my signature in the presence of two witnesses.
